HEDDLE FRAME

Louis Kasper, Philadelphia, Pa., assignor to Steel
Heddle Manufacturing Company, Philadelphia,
Pa., a corporation of Pennsylvania

Application July 16, 1935, Serial No. 31,552

9 Claims. (Cl. 139—92)

My invention relates to heddle frames for looms, and more particularly to improved means for supporting the heddle supporting bars intermediate their ends in a harness frame.

5 The principal object of the present invention is to provide, in a heddle frame, a self-locking heddle bar support which will receive and hold a heddle supporting bar intermediate the ends of the bar and will prevent movement and dis-
10 placement of the heddle bar, but which will permit easy and quick removal of the heddle supporting bar from the harness frame when desired.

A further object of the invention is to pro-
15 vide a heddle bar support which will be spring pressed to locking position and will be self-locking, but which may be readily released and actuated to a position to permit the removal of the heddle bar.

20 A further object of the invention is to pro-
vide a heddle bar support which will contain within itself means for automatically locking a heddle bar in fixed position.

25 A further object of the invention is to provide a heddle bar support which will be simple and inexpensive in construction, yet sturdy and reliable in operation. Other objects of the invention will appear from the specification and claims.

The nature and characteristic features of the 30 invention will be more readily understood from the following description, taken in connection with the accompanying drawing forming part hereof, in which:

35 Figure 1 is an elevational view of a heddle frame provided with heddle bar supporting devices embodying the main features of the present invention;

40 Fig. 2 is an enlarged fragmentary side elevational view partly in section, illustrating one of the supporting devices, the same being shown in conjunction with a portion of the rail of the heddle frame on which it is mounted, and showing the parts in position to lock the heddle bar in position;

45 Fig. 3 is a view similar to Fig. 2, but showing the supporting device in the open position for the insertion or removal of a heddle supporting bar;

50 Fig. 4 is an enlarged sectional view, taken approximately on the line 4—4 of Fig. 1 and showing the parts in the locked heddle bar supporting position, as in Fig. 2; and

Fig. 5 is a sectional plan view taken on the line 5—5 of Fig. 3.

55 It will, of course, be understood that the de-

scription and drawing herein contained are illustrative merely, and that various modifications and changes may be made in the structure disclosed without departing from the spirit of the invention.

5 Referring to the drawing, the heddle frame there shown comprises top and bottom rails 10, connected at their ends by means of side strips 11. Heddle supporting bars, as at 12, extend from end to end of the heddle frame, near the top and bottom rails 10. Heddles 13 are mounted on the heddle supporting bars 12 in the usual manner.

The heddle bar supporting devices comprising the improvement of the present invention are 15 mounted at suitable locations on the inner edges of the top and bottom rails 10. Each of the heddle bar supporting devices includes a pin or bolt member 20, having a shank 21, and the end portion thereof is threaded for engagement with 20 the wooden rails 10, as at 22, in a manner similar to an ordinary wood screw, with the exception that the same is not tapered for the greater portion of its length.

25 The bolt member 20 is also provided with a flattened head portion 23, offset as at 24 with respect to the vertical axis of the shank 21, so that one face thereof, as at 25, is substantially in alignment with the outside of the shank 21. The head portion 23 is preferably made by flattening 30 and spreading the material of the rod from which the bolt member 20 is formed.

35 The flattened head portion 23 is recessed as at 26, and a notched shoulder 27 is provided for heddle bar engagement. A shoulder 28, provided 35 at the opposite end of the recess 26, is slightly inclined as indicated in Fig. 4, to facilitate the insertion and removal of the heddle supporting bar 12.

40 A slidable heddle bar clamping member 29 is mounted on the face of the flattened head portion 25 of the bolt member 20, and includes, at the end thereof toward the free end of the pin 20, a slotted portion 30 for direct engagement with the edge portion of the heddle bar 12. 45

The other end of the bar clamping member 29 is bent over, as at 31, perpendicular to the axis of the shank portion 21 of the bolt member 20, and is provided with an aperture 32 through which the shank portion 21 extends, so that 50 vertical sliding movement of the bent over portion 31 along the shank 21 is readily effected.

55 The other end portion of the bar clamping member 29, which carries the slotted portion 30, is positioned with respect to the head portion 23 55

of the bolt member 20 by means of a rivet 33 which extends through a slot 34 in the bar clamping member 29. The slot 34 serves also to limit the movement of the bar clamping member 29 along the pin 20, and prevents said member from moving an excessive distance toward the free end of the bolt member 20 when no supporting bar is seated within the recess 26.

A locking lever member is provided as at 35, having an aperture 36 therethrough, the width of which is substantially equal to, but the length of which is slightly greater than the diameter of the shank 21, to permit the lever member 35 to assume the angular or inclined locking position shown in Fig. 2.

The lever member 35 has a bent over end portion, as at 37, with a tongue 38 extending into a cut out portion 39 of the slideable clamping member 29. The tongue 38 and the cut out portion 39 provide, with the top of the bent over portion 31, a suitable pivotal or hinge connection and a fulcrum for the lever 35. The end of the lever member 35 opposite the end portion 37 is bent back as at 40, to provide a lip 41 for engagement with a face of the bent over portion 31.

The lip 41 furnishes a part for engagement by the operator, and is so arranged that the lever 35 may be swung from the angular position, as shown in Fig. 2 to a position parallel to the bent over portion 31 of the clamping member 29, as shown in Fig. 3. The movement of the lever member 35 to the parallel position, as shown in Fig. 3, is limited by the engagement of the back turned lip portion 41 with the under face of the bent over portion 31 of the clamping member 29. In this latter position, the clamping member 29 is unlocked, and may thereafter be easily moved to a position to permit the insertion or removal of the heddle bar 12.

A coil spring 42 is mounted on the shank 21 of the bolt member 20. The coil spring 42 bears at one end against the locking lever member 35 and at the other end against struck up portions 43 on the shank 21, if it is desired to provide a predetermined tension not varied by the adjustment of the bolt 20 in the rails; or this latter end may bear against a portion of the rail if desired.

The operation of the device will now be readily understood. In the position prior to the insertion 50 of a heddle bar 12, the locking lever member 35 is at an angle, somewhat as shown in Fig. 2, and assuming that it is desired to mount a heddle bar 12 in the support, the locking lever 35 is first pushed manually to a position parallel to the bent over portion 31, by application of force to the bent under portion 41 and against the tension of the coil spring 42. Upon the continued application of force the locking lever member 35 and the slideable bar clamping member 29 are moved together to the position shown in Fig. 3.

The heddle bar 12 may then be inserted in the recess 26, and the manual force withdrawn. The coil spring 42 then forces the locking lever 35 and the slideable clamping member 29 toward the free end of the bolt member 20 until further movement is prevented by engagement of the end of the slotted portion 30 with one edge portion of the heddle bar 12, the other edge portion of the bar being held in engagement with the shoulder 27 of the bolt member 20.

The coil spring 42 maintains the locking lever 35 in the inclined position as shown in Fig. 2, and any force exerted by the rod 12 on the slideable clamping member 29 is transmitted through its fulcrum to the locking lever 35. The

engagement between the inner portions of the aperture 36 of the locking lever 35, and the shank portion 21, is made tighter and firmer as the force is increased, while at the same time the spring 42 assists in maintaining the locking lever 35 in its locking position. It will thus be seen that the device is self-locking at all times when a heddle bar 12 is in the recess 26.

If it is desired at any time to remove the heddle bar 12, it is a relatively simple matter to 10 operate the device in the manner pointed out above for the initial insertion of the heddle bar 12.

I claim:

1. The combination with a heddle frame, of a 15 pin mounted on the rail thereof and having a shoulder adapted to receive a heddle bar, a clamping member for engagement with the heddle bar, and positive locking means gripping said pin for holding said clamping member in engagement with the heddle bar, said means being self-locking with respect to the pin.

2. A heddle bar support including a pin having a shoulder adapted to receive a heddle bar, said pin also having a shank portion, a member slidably mounted on said pin for holding the heddle bar against said shoulder, and means for locking said member in heddle bar engaging position, said means including a lever mounted on said member, said lever having an aperture through 30 which said shank passes, and means for urging said lever into shank engaging relationship.

3. The combination with a heddle frame, of a pin mounted on the rail thereof and having a shoulder adapted to receive a heddle bar, said 35 pin having a shank portion, a clamping member mounted on said pin for engagement with the heddle bar, and a spring pressed locking member on said clamping member for gripping engagement with said shank portion.

4. The combination with a heddle frame, of a pin mounted on the rail thereof and having a shoulder adapted to receive a heddle bar, said pin having a shank portion, a clamping member slidably mounted on said pin for engagement with the heddle bar, a locking member mounted on said clamping member for locking engagement with said shank portion, and a spring normally urging said locking member to heddle bar locking position.

5. The combination with a heddle frame, of a pin mounted on the rail thereof and having a shoulder adapted to receive a heddle bar, said pin having a shank, a clamping member slidably mounted on said pin for engagement with the heddle bar, said clamping member having a laterally extending portion, a locking member mounted on said laterally extending portion for engagement with said shank portion, and a spring on said shank portion normally urging 60 said locking member to heddle bar locking position.

6. The combination with a heddle frame, of a pin mounted on the rail thereof and having a shoulder adapted to receive a heddle bar, said 65 pin having a shank portion, a clamping member slidably mounted on said pin for engagement with the heddle bar, said clamping member having a laterally extending portion through which the shank passes, a locking lever mounted on 70 said laterally extending portion and having an aperture through which the shank passes, and a spring on said shank portion normally urging said locking lever to gripping engagement with said shank portion.

7. A heddle bar support including a pin having a shoulder adapted to receive a heddle bar, said pin having a shank portion, a clamping member slidably mounted on said pin for holding the heddle bar against said shoulder, and means for locking said clamping member in heddle bar engaging position, said means including a lever mounted for pivotal movement with respect to said clamping member, said lever being movable from a free position to a shank gripping position at an angle to said free position, and a spring for urging said lever into said shank gripping position.

8. A heddle bar support including a pin having a shoulder adapted to receive a heddle bar, said pin having a shank portion, a clamping member slidably mounted on said pin for holding the heddle bar against said shoulder, said clamping member having a laterally extending portion and means for locking said clamping member in heddle bar engaging position, said means including a locking lever mounted on said laterally extending portion, said lever having a portion through which said shank passes, said lever being movable from a predetermined position

with respect to said laterally extending portion to a shank gripping position at an angle to said first mentioned position, and a coil spring for urging said lever into said shank gripping position.

9. A heddle bar support including a pin having a shoulder adapted to receive a heddle bar, said pin having a shank portion, a clamping member slidably mounted on said pin for holding the heddle bar against said shoulder, said clamping member having a laterally extending portion through which the shank passes, and means for locking said clamping member in heddle bar engaging position, said means including a locking lever mounted on said laterally extending portion, said lever having an aperture through which said shank passes, said lever being movable from a free position parallel to said laterally extending portion to a shank gripping position at an angle to said laterally extending portion, and a coil spring mounted on said shank for urging said lever into shank gripping position.
